(Cl. D57—1)

Fig.1.

Fig.2.

Fig.3.

Fig.4.

FIGURE 1 is a front perspective view of an illuminator casing for microscopes showing my new design;
FIGURE 2 is a front elevational view thereof;
FIGURE 3 is a rear elevational view thereof; and
FIGURE 4 is a top plan view thereof.

The appearance of my illuminator casing for microscopes is substantially the same when viewed from either side thereof and the bottom is flat and unornamented.

I claim:
The ornamental design for an illuminator casing for microscopes, as shown and described.
